LOUIE F. METCALF, OF GREENVILLE, ALABAMA, ASSIGNEE TO FLORENCE D. METCALF,
OF GREENVILLE, ALABAMA.

UNION WORKING GARMENT.

1,411,119.

Specification of Letters Patent. Patented Mar. 28, 1922.

Application filed March 23, 1921. Serial No. 454,651.

To all whom it may concern:

Be it known that I, LOUIE F. METCALF, a citizen of the United States, residing at Greenville, in the county of Butler and State 5 of Alabama, have invented certain new and useful Improvements in Union Working Garments, of which the following is a specification.

The present invention relates to union 10 working suits, that is to say, a one piece working suit comprising a coat portion and a trousers portion, such as workmen engaged in dirty work will wear. The object of the invention is to produce a union overall garment which will be neat in appearance, easy 15 to manufacture, which will have good wear-resisting properties and which will hold its shape and which can be easily put on and taken off by the user.

20 The accompanying drawings show the important novel features. Figure 1 is a front view of the garment spread out. Figure 2 is a rear view of the same, a portion of the back being broken away to more fully show 25 the back flap of the coat portion. Figure 3 is a detailed view of the side, the back flap of the trousers portion being broken away to show the downwardly extending back flap of the coat portion. Figure 4 is a sectional 30 view on line 4-4 of Figure 1 showing the pocket, the reinforcement of the breast portion of the coat above the pocket and the button for holding the front end of the suspenders. Figure 5 is a section of the outside 35 edge of the trousers portion, showing the back portion of the trousers overlapping the front portion thereof, the two being joined in a felled seam. Figure 6 is a section showing the belt and the manner of attaching 40 the belt to the coat and to the trousers portion, this section being taken, for example on the line 6-6 of Figure 1. Figure 45 7 is a section on the line 7-7 of Fig. 2, and shows a preferred manner of forming the neck-band and collar. Figure 8 is a front view of a modified form, showing a sewed-on bib portion. Figure 9 is a modified form 50 of the back portion, showing the back flap and suspenders made integral with each other.

Referring now more particularly to the structure shown in Figures 1 to 7 inclusive: The entire garment may be made of such

55 materials as are commonly used for the purpose, for example ordinary denim. The entire front from the neck down to the crotch opens and is provided with suitable buttons, or other fastening means for closing the same. At the top of the trousers the garment opens on both sides from the belt downwards, the belt itself being integral at the sides, and the back flap being provided with button holes which engage buttons 10 for closing the same. The back flap 11 extends upwards a short distance above the waist 60 line in the back and is attached to suspenders 12 which go over the shoulders, the front ends being capable of being attached to buttons 13, for example by the wire button-holes 14 carried on the front ends of the suspenders. At 15 is an adjustable buckle whereby the length of the suspenders may be adjusted according to the proportions of the wearer. At 16 are shown reinforcements placed above the breast pockets, the 65 element 16 on the right hand side of the body being stitched to the coat portion, for example by a double line of stitching extending all around the same. If desired on the left hand side of the coat the bottom of the 70 element 16, the top of the pocket and the material of the coat itself may be all stitched together, this pocket being opened on the side. Completely encircling the body on the 75 inside of the garment is the belt 18, this belt being broken only at the front and a button 80 19 being provided cooperating with a buttonhole to securely fasten the same when the garment is put on. The belt is stitched at its upper and lower margins after being 85 turned in as shown in Figure 6, this belt 90 greatly strengthening the entire structure.

95 A feature of importance in making the garment in such a way that it will hold its shape well is the provision of seams in the trousers portion, both on the inside extending from the crotch down to the bottom end and on the outside extending from the lower edge of the side opening 21 down to the bottom. This outside seam 22 is particularly shown in Figure 5. In said figure 23 represents the back portion of the leg of the garment and 24 represents the front portion. It will be noted that this is a felled seam, the part 23 overlapping and the edge 100 105 of this being brought back outside of the

front portion 24 and the edge of 24 is brought forward inside of 23 but outside of the lapped over edge portions thereof. The seam is then finished by a double row of stitching which gives great strength to the leg portions and the two seams referred to serve to prevent the legs from getting out of shape due to the strains to which the garment will necessarily be subjected during ordinary wear.

In the rear of the coat, and inside of the flap 11, is a downwardly extending flap 25, this flap extending across the back of the body from the side opening on one side to the side opening on the other side. This piece is completely concealed by the upwardly extending flap 11 of the trousers when in use. On the back of the hips are sewed the ordinary pockets 26 in the usual manner.

27 represents the openings of the front pockets, the upper ends of the pockets themselves being stitched in with the bottom of the belt.

25 The coat body is preferably made of four pieces, two half-fronts 30 and 31, and two half-backs 32 and 33, stitched together as shown.

30 At the top of the coat is a double neck band, composed of an inner band 34, an outer band 35, to which are preferably attached a double collar 36. The manner of assembling these is clearly shown in Figure 7.

35 The sleeves 39 are preferably provided with front seams 40 and back seams 41. At the cuff is a split or opening 42, buttons 43 and 44 being provided for closing the same.

40 A modification of the upper part of the front of the garment is shown in Figure 8 of the drawings; this modification showing a bib on the front of the jacket portion. This bib preferably carries side pockets, the openings of which are illustrated at 50, the 45 edge of the bib above the pockets, and across the top being stitched to the jacket. The bib is split at 51, to aline with the split 52 in the jacket proper, and the edges of the split of the bib are stitched to the edges of 50 the split of the jacket. As shown, the button 13 for attachment of the suspenders, is attached close to the top of the bib, near the corners. These buttons are preferably attached by a rivet extending through both 55 bib and coat, to give greater strength and rigidity. Additional tab pockets may, if desired, be placed on the bib, as shown at 52'. These are preferably stitched to the bib but not to the coat. Additional stitching, for 60 reinforcement for the buttons, may be made as shown at 53.

The provision of this bib, with its stitching all around except at the pocket openings, makes a double thickness and hence additional strength at the front where the

greatest strain comes, and hence makes the garment more durable as well as giving greater firmness to the front of the garment.

A further modification which is also frequently useful is that shown in Figure 9, 70 which is a view of the upwardly extending back flap of the trousers. In this construction, the back flap 54 is made integral with the suspenders, thereby doing away with the seam connecting these, and the lines of 75 stitching shown greatly strengthen the back flap and the suspenders.

The pockets provided as shown in the different figures are suitably provided with openings. The right hand breast pocket in 80 Fig. 1 may have an opening at its top as shown at 60. The left hand breast pocket may have an opening at its side as shown at 61. A small side pocket on the right hand side of the leg of the garment may be provided as shown at 62, this pocket opening at 63. Above the right hand pocket in the front of the trousers portion there may, if desired, be provided a small pocket with an opening at 64, for holding small articles 90 such as matches and the like. As shown in Fig. 2, the rear pockets 26 are open at their tops 65. As shown in Fig. 8, the breast pocket 52' may open at 66.

As shown in Fig. 8, an additional button hole may be provided at 68. This button hole may be used to accommodate the end of a watch chain, the watch being carried for example in the breast pocket 52'. 95

I claim:

1. A union working garment comprising a coat portion and a trousers portion, and a belt stitched thereto, completely encircling the body, the coat portion being provided with a rear flap extending downwardly from 105 the belt, the trousers portion being provided with a back flap extending upwardly and carrying suspenders, fastening means on the front of the chest of the coat portion to which such suspenders may be attached, the fabric of the coat being reinforced in proximity to said fastening means, the trousers portion being provided with felled outside seams, the back part of the trousers overlapping the front part thereof, an overlapping 110 buttoned fly at each side, including the belt and extending downwardly therefrom, the back portion overlapping the front portion in said fly. 115

2. In a working garment, a trousers portion having seams on the outer sides of the legs, said seams being formed by overlapping the rear leg portion upon the front leg portion nearly up to the waist line, to leave a side opening, the rear of said trousers portion being provided with a drop seat the edges of which are adapted to overlap the corresponding portion of the front at about the waist line and above the bottom of said side opening, means for securing the edges 120 125 130

of the drop seat in such overlapped position, 5
suspenders attached to the top of said drop
seat, and means for attaching the free ends
of said suspenders to the front of said gar-
ment.

3. In working garments a trousers por-
tion, having seams on the inner side of the
legs and also having felled seams on the
outer side of the legs, the seams at the outer
10 side of the legs being formed by overlapping
the rear leg portion upon the front leg portion,
in combination with a drop-seat car-
ried by the upper part of the back of the
trousers.

15 4. A union working garment having a
trousers portion and a jacket portion, the
back of the trousers portion having a drop
seat, suspenders attached to the top of said
drop seat and passing over the shoulders,
20 breast pockets stitched to the jacket portion,
reinforcement strips stitched to the jacket
portion partly below and partly above the
tops of said pockets, said strips being
stitched at their side edges at least to said

pockets, such strips being stitched all around 25
to the coat portion, and being wider at the
bottom than at the top, and buttons attached
to said reinforcement strips and to the coat
portion near the tops of such strips, to which
buttons the said suspenders are attachable. 30

5. A union working garment having a
trousers portion and a jacket portion, the
back of the trousers having a drop seat, sus-
penders attached to the top of said drop seat
and passing over the shoulders, breast pock- 35
ets stitched to the jacket portion, reinforce-
ment strips stitched to the jacket portion
partly below and partly above the tops of
said pockets, said strips being stitched al-
around their edges to the coat portion, and 40
a single button attached to each of said rein-
forcement strips at its upper part, which
button is also attached to the coat portion
lying under such strips, to which buttons the
said suspenders are attachable. 45

In testimony whereof I affix my signature.

LOUIE F. METCALF.
